SMOKING IMPLEMENT

Louis N. Sobel, New York, N. Y.

Application March 24, 1948, Serial No. 16,769

4 Claims. (Cl. 131—188)

1

This invention relates to smoking implements, and more particularly to implements of the type which prevent the passage of loose particles of tobacco to the smoker's mouth.

It is the primary object of the present invention to provide in a cigar holder or pipe an implement which successfully keeps loose particles of tobacco from the usual passage through which smoke is conducted to the user's mouth and in which saliva may readily accumulate, thereby eliminating not only the biting sensation experienced when loose particles of tobacco get into one's mouth, but also the bad taste and smell which is so often encountered by smokers when tobacco and saliva mix in the smoke passage of a cigar holder or pipe.

It is another important object of the present invention to provide in a cigar holder or pipe an implement of this type which does not readily become clogged, does not require replacement, does not interfere with, or in any way modify, the accustomed response to the user's draw for smoke, and is readily cleaned without requiring any skill.

The above and other objects, features and advantages of the present invention will be more fully understood from the following description considered in connection with the accompanying illustrative drawings.

In the drawings:

Fig. 1 is an enlarged side elevational view of a cigar holder embodying the present invention;

Fig. 2 is a longitudinal section through the holder as taken on the line 2—2 of Fig. 1;

Fig. 3 is an enlarged longitudinal section through a detail of the holder; and

Fig. 4 is a side elevation, partly in section, of a pipe embodying the present invention in a modified manner.

Referring to the drawings, and more particularly to Figs. 1 and 2 thereof, the reference numeral 10 designates a cigar holder which, in the present instance, comprises a mouth piece 12 and a receptacle 14 for the end of cigar C. The parts 12 and 14 of the holder 10 are, in the present instance, held in the assembled relation shown by means of a short sleeve 16, which is threadedly received at 18 in the mouth piece 12 and is provided with a collar 20 for drawing the receptacle 14 into firm engagement with the mouth piece 12.

Press fitted or otherwise suitably secured in the sleeve 16, and preferably additionally attached thereto as by brazing, for instance, is a shell-like element 22 which may advantageously

be made from a strip of sheet metal or any other suitable material that is twisted in any suitable manner into the spiral shape shown in Figs. 2 and 3. Preferably successive turns or convolutions of the spiral element 22 are formed gradually narrower so that the latter will be tapered, at least that part thereof which projects from the sleeve 16. The outer end of the spiral element 22 may be worked in any suitable manner into a substantially closed and relatively sharp tip 24. Thus a continuous spiral gap 28 is provided in the wall of the shell-like element 22 which constitutes a very considerable area of communication between the outside of the element and the interior 26 thereof, yet the spiral gap 28 does not extend to the tip 24 of the element which is advantageous as explained hereinafter.

In using the holder 10, a cigar C is forced into 20 the receptacle 14, whereby the end e of the cigar becomes impaled on the element 22 in the fashion shown in Fig. 2. Due to the provision of the relatively sharp tip 24 on the element 22, the cigar C will require very little forcing in order 25 to become properly impaled on the element 22. The cigar C is preferably forced into the receptacle 14 so that it bears against the sleeve 16 in the manner shown in Fig. 2, in order that the spiral gap 28 in the element 22 may provide 30 communication only between the impaled cigar C and the smoke passage 30 in the mouth piece 12.

In order more firmly to hold the cigar in the receptacle 14 and prevent its breakage in the vicinity of the element 22 on which it is impaled, there is slidably on the periphery of the receptacle 14 a holding sleeve 32 which may be extended thereon in the manner shown in Figs. 1 and 2 so as firmly to grip the cigar and hold it more securely in the receptacle 14.

The relatively long spiral gap 28 in the element 22 forms a passage between the interior of the cigar and the interior 26 of the element 22 through which the customary amount of smoke 45 may readily pass in response to the user's accustomed draw. The interior 26 of the element 22 is also of sufficient cross-sectional area to conduct, without obstruction, all the smoke that may be drawn from the cigar by the user. Since the spiral gap 28 does not extend clear to the tip 24 of the element 22 which pierces the end of the cigar when the latter is inserted into the receptacle 14, the gap 28 is not liable to become readily clogged, and will always remain sufficiently open 55 so as not to interfere with the accustomed smok-

ing enjoyment by the user even if part of this gap should become clogged with loose tobacco. Further, the considerable area of communication between the exterior and interior of the element 22, as constituted by the spiral gap 28 therein, affords the possibility to make the element 22 of relatively small diameter without obstructing the passage through the element of all the smoke that may possibly be drawn by a smoker.

Fig. 4 illustrates a modified application of the instant invention to a conventional pipe 40. Thus, a spirally wound element 22' of the same general construction as the previously described element 22 may be press-fitted in a sleeve 16' that may threadedly be received at 18' in the pipe 40, so that the interior of the spiral element 22' is in permanent communication with the passage 42 in the pipe that leads to the mouth piece 44. The element 22' differs from the previously described element 22 in that the closed tip 46 thereof in the bowl 50 of the pipe is more or less smoothly rounded in any suitable manner. The round or dull tip 46 of the element 22' is essential to protect the fingers of the pipe smoker when packing tobacco into the bowl 50 of the pipe, as will be readily understood. The spiral gap 28' in the element 22' admits to the passage 42 in the pipe all the smoke that the smoker can possibly draw, yet this gap 28' effectively prevents loose particles of tobacco from reaching the passage 42 in which saliva is liable to accumulate, depending on the smoking habits of the user. Thus, if saliva should accumulate in the passage 42, at least no tobacco may mix with it and spoil the smoker's taste for his pipe.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent, is:

1. In a cigar holder having a receptacle adapted to hold the end of a cigar, a mouthpiece and a smoke passage between said receptacle and mouthpiece, a shell-like element having one end formed as a closed, relatively sharp tip and adapted to fit with its open end in said passage, said element adapted to project into said receptacle so as to penetrate a cigar inserted endwise into said receptacle, and having in its wall at least within the confines of said receptacle a spiral gap which extends through said wall, said spiral gap being formed of relatively closely spaced convolutions whereby to prevent the passage of loose particles of tobacco therethrough.

2. In a cigar holder having a receptacle adapted to hold the end of a cigar, a mouthpiece and a smoke passage between said receptacle and mouthpiece, a shell-like element having one end

formed as a closed, relatively sharp tip and adapted to fit with its open end in said passage, said element adapted to project into said receptacle so as to penetrate a cigar inserted endwise into said receptacle, and having in its wall at least within the confines of said receptacle a spiral gap which extends through said wall, said spiral gap having its successive convolutions gradually narrower toward said sharp tip and said element being at least within the confines of said receptacle tapered toward the tip thereof whereby to prevent the passage of loose particles of tobacco therethrough.

3. In combination with a cigar holder having a cup-like receptacle with a cylindrical outer periphery and being adapted to hold the end of a cigar, a mouthpiece and a smoke passage between said receptacle and mouthpiece, a shell-like element having one end formed as a closed, relatively sharp tip and adapted to fit with its open end in said passage, said element adapted to project into said receptacle so as to penetrate a cigar inserted endwise into said receptacle, and having in its wall at least within the confines of said receptacle a spiral gap which extends through said wall, and a cylindrical sleeve slideable on the outer periphery of said receptacle and adapted to serve as an extension of said receptacle for additionally holding a cigar inserted in the latter, said sleeve and said element thereby supporting a cigar in said receptacle.

4. An insert for a cigar holder having a receptacle adapted to hold the end of a cigar, a mouthpiece and a smoke passage between said receptacle and mouthpiece, comprising a shell-like element having one end formed as a closed, relatively sharp tip and being adapted for fitted reception with its open end in said passage so as to project with the remainder of its length into said receptacle, said element having in its wall a spiral gap which extends through said wall, said spiral gap being formed of relatively closely spaced convolutions whereby to prevent the passage of loose particles of tobacco therethrough.
